VACUUM SWEEPER

James F. Mariol, Cincinnati, Ohio, assignor to Vernco Corporation, Columbus, Ind., a corporation of Indiana

Filed Apr. 16, 1968, Ser. No. 11,483

Term of patent 14 years

Int. Cl. D7—06

U.S. Cl. D49—14.1

FIG. 1 is a perspective view, drawn to a reduced scale, of a vacuum sweeper embodying my design;
 FIG. 2 is a top plan view thereof;
 FIG. 3 is a side elevational view thereof; and
 FIG. 4 is another side elevational view thereof seen generally from the left-hand side of FIG. 3.
 I claim:

The ornamental design for a vacuum sweeper, as shown and described.
